UNITED STATES PATENT OFFICE.

WILLIAM N. WHITE, OF FORTYFORT, PENNSYLVANIA.

TRAVELING CHUTE FOR COAL-POCKETS.

1,061,151.

Specification of Letters Patent.

Patented May 6, 1913.

Application filed October 10, 1912. Serial No. 724,987.

To all whom it may concern:

Be it known that I, WILLIAM N. WHITE, a citizen of the United States, residing at Fortyfort, in the county of Luzerne and 5 State of Pennsylvania, have invented a new and useful Traveling Chute for Coal-Pockets; and I do hereby declare the following to be a full, clear, and exact description of the invention, such as will enable 10 others skilled in the art to which it appertains to make and use the same.

This invention relates to a new and useful traveling or movable chute for coal pockets.

One of the objects of the invention is the 15 provision of a traveling or movable chute operative upon an inclined track, and provided at the lowest end thereof with a spreader plate of the shape shown in the drawings for evenly spreading the coal in 20 the upper portion of the pocket, against a regulating plate projecting downwardly from the under surface of the lowest end of the movable chute, and as the coal piles up against the regulating plate the movable 25 coal chute is moved upwardly upon the inclined track, so as to gradually regulate the coal down the incline of the pocket, where it passes through a gate opening.

In practice there is a series of pockets, 30 and each gate opening of each pocket is opened or closed by means of a gate, there being an attendant, known in practice as a "loader", for operating each gate. When it is desired to load a car at the gate opening, the "loader" gives the signal in any suitable manner, and the coal is allowed to pass from the coal regulator, upon the traveling chute, from which it is spread into the pocket, then the "loader" opens the 40 gate, thus allowing the coal to flow into the car.

Another object of the invention is the provision of a counterbalance weight, which assists in moving the movable chute up the 45 inclined track, as the coal is deposited against the regulating plate.

In the drawings there are disclosed certain features of construction, and in practical fields these features may necessitate 50 alterations, to which the patentee is entitled, provided the alterations fall within the scope of what is claimed.

The invention comprises further features and combination of parts, as herein-

after set forth, shown in the drawings and 55 claimed.

In the drawings:—Figure 1 is a vertical sectional view through a coal pocket, showing the application of the improved traveling or movable chute. Fig. 2 is an end elevation of the lowest end of the traveling chute. Fig. 3 is a detail perspective view of the lowest end of the traveling chute. Fig. 4 is a detail view of the spreader plate.

Referring more particularly to the drawings 65 1 designates a coal regulator, of any suitable construction, for instance, a structure similar to that shown in the Patent 1,008,684. The coal leaves the regulator 1, and is deposited upon the traveling chute 2, 70 which is constructed of sheet metal having upturned sides 3, or of any other suitable material. The chute 3 is mounted upon the wheels 4, which engage the tracks 5 of the beams 6. The rails 5 and beams 6 are 75 disposed on an incline, as shown in the drawings over the upper portion of a coal pocket 7, the floor of which is constructed on an incline, but in a reverse direction to that of the rails 5.

The lowest end of the movable or traveling coal chute is provided with a spreader plate 9, which is constructed of sheet metal, and arranged at an angle to the chute. This spreader plate is provided with a central 85 raised portion 10 and slight V-shaped gulleys 11, one upon each side of the raised portion, so as to properly and evenly spread the coal upon the upper portion of the inclined bottom 8 of the pocket, and against 90 the regulating plate 12. The spreader plate is bolted or otherwise secured at 13 to the traveling or movable chute, the same being braced by the beam 14, which in turn is bolted or otherwise secured to the traveling 95 chute.

The regulating plate 12 is secured to the brace bars 15 in any suitable manner, which bars 15 are angular in cross section. Additional braces 16 are secured at 17 and 18 to 100 the bars 15 and the traveling chute, so as to reinforce and brace the bars 15. The bars 15 and 16 project downwardly from the traveling chute and are disposed between the rails, while the regulating plate 12 is arranged transversely of and below the rail. This regulating plate is of considerable length, so as to accommodate a large quan-

- tity of coal thereagainst, and the pressure of this coal against said plate is sufficient to move the traveling chute up the inclined rails. The counterbalance weight 19 assists 5 the deposit of coal against the plate 12 to impart this upward movement to the traveling chute. The counterbalance weight 19 is attached to a cable 20, which passes over the pulley 21, and the end 22 of the cable is attached at 23 to the traveling chute. As the traveling chute is moved up the inclined rails, the space 24 between the regulating plate and the inclined floor of the pocket, it will be noted, becomes larger. The lower 10 portion of the pocket, there only being one shown, is provided with a gate opening 25, which is controlled by the usual form of gate 26, which may be operated by an attendant, known as a "loader."
- 15 20 From the above description in connection with the annexed drawings, it will be observed that there has been devised a simple, efficient and desirable traveling or movable chute for coal pockets, and one which has 25 been found practical. In practice the construction and the disposition of the various parts of each coal chute are to accord with the grade and the size of the coal, so as to insure the proper operation and application 30 of the improved apparatus.
- The invention having been set forth, what is claimed as new and useful is:—
1. In combination, a coal pocket having an inclined bottom, a track in the upper portion of the pocket disposed on an incline in a reverse direction to that of the floor of the pocket, a traveling chute mounted upon the inclined track having a counterbalance weight connected to the upper rear end of the 35 chute, and a plate projecting downwardly from and transversely of the under portion of the forward end of the chute, against which the coal from the chute is deposited, to automatically move the chute up the in- 40

clined track, the counterbalance weight constituting means assisting in imparting this movement to the chute. 45

2. In combination, a coal pocket having an inclined bottom, a track in the upper portion of the pocket disposed on an incline in a reverse direction to that of the floor of the pocket, a traveling chute mounted upon the inclined track having a counterbalance weight connected to the upper rear end of the chute, and a plate projecting downwardly from and transversely of the under portion of the forward end of the chute, against which the coal from the chute is deposited, to automatically move the chute up the inclined track, the counterbalance weight 50 constituting means assisting in imparting this movement to the chute, the traveling chute having a spreader plate at its lower end, said spreader plate being constructed with a centrally raised portion with a V-shaped gulley on each side thereof, whereby 55 the coal may be evenly distributed against the plate. 60

3. In a traveling chute construction, a movable chute disposed on an incline and having a vertically and transversely arranged plate thereunder at the forward end, a spreader plate carried by the lowest end and arranged at an angle to the chute, said spreader plate being constructed with a cen- 65 trally raised portion with a V-shaped gulley 70 on each side thereof, whereby the coal may be evenly distributed or spread against the regulating plate, and an inclined track on which said traveling chute is operable. 75

In testimony whereof I have signed my name to this specification in the presence of two subscribing witnesses. 80
